PRESSURE GAUGE

Ralph D. Waite, Sellersville, Pa., assignor to
Ametek, Inc., New York, N.Y.

Filed Feb. 19, 1971, Ser. No. 117,222

Term of patent 14 years

Int. Cl. D10—04

U.S. Cl. D52—6

FIG. 1

FIG. 2

FIG. 3

FIG. 4

FIG. 5

FIG. 1 is a front elevation view of a pressure gauge showing my new design;

FIG. 2 is a side elevational view thereof;

FIG. 3 is a rear elevational view thereof;

FIG. 4 is a side elevational view of FIG. 1 in partial section showing the stepped contour of the rear surface;

FIG. 5 is a front perspective view of FIG. 1 with one-half of the dial cover cut away to illustrate the stepped dial appearance.

I claim:

The ornamental design for a pressure gauge, substantially as shown and described.
